UNITED STATES PATENT OFFICE.

JOSEPH ROBINSON, OF NEW YORK, N. Y.

AUTOMATIC TRAIN-PIPE CONNECTER.

Application filed March 22, 1921, Serial No. 454,545. Renewed November 3, 1925.

My invention relates to improved automatic train pipe connectors, and it consists in the constructions, combinations and arrangements hereinafter described and claimed. Among the objects of my invention is to provide an improved means of connecting a car having the connector to one not equipped therewith, and to provide an improved coupling head on which the guiding means therefor is adjustably mounted.

I accomplish this end by a novel form of interchange coupling which is mounted on the wing of the coupling head, the wing being pivoted to the head and adapted to be swung across the face thereof, thus bringing the interchange coupling in line with the port in the head and adapting it to receive the hose of the unequipped car.

In the accompanying drawings forming a part of this application, and in which similar reference symbols indicate corresponding parts in the several views,

Figure 1 is a front elevation of my improved coupling head.

Figure 2 is a section thereof on the line 2—2 of Figure 1, looking upward in the direction of the top of the head, and

Figure 3 is a detailed view showing the latch for locking the pivoted wing of my improvement in interchange position.

Referring now to the drawings: Any suitable form of support may be used to carry my improved coupling head and interchange, a support such as that shown in my United States Letters Patent #1,245,773, granted November 6, 1917, for improvements in train pipe connectors, being entirely suitable. The coupling head B is of the conventional butt face form and is provided with a pair of diagonally spaced forwardly extending outwardly diverging guiding prongs 4 the upper one of which is pivoted to the side of the head as by a vertically extending pin 5 threaded at 6 and screwed into the head at this point to secure the pin in position. The upper prong 4 is locked in the normal operative position—shown in Figure 1—by any suitable means, such as a key or pin 7, extending through perforated ears 8 and 9 on said upper guiding prong and head, respectively. The upper prong is provided with a port 10 adapted to register with the port 11 in the connector head B. The port 10 extends through a conventional form such as the

Westinghouse type of air hose hand coupling 12, formed with, or otherwise connected to, the rear face of the upper prong 4. The coupling 12, when swung across the face of the coupling head B, as hereinafter described, serves to connect the hose of an unequipped car with interchange communication with the head B. When it is desired to make interchange with a car not equipped with the automatic connector, the pin 7 is removed and the upper prong 4 is swung across the face of coupling head, as indicated by broken lines in Figure 2. It is locked in this position by a rod or latch 13 extending freely through the upper prong 4 and provided with a threaded end 14 adapted to screw into a threaded opening 15 in the connector head B; said rod being normally maintained in retracted position by a spring 16, and provided with a stop 17 engaging a recess in the upper prong 4 thus firmly locking the rod against rattling and play.

The foregoing construction comprehends a butt face coupling head of the wing type in which a guiding means therefor is pivoted to the head and may be adjusted thereon or entirely detached therefrom upon occasion, and in which also such guiding means may be folded across the face of the coupling head to effect interchange with a car not having the automatic connector. The latch or pin 7 may be regarded as means for locking the upper prong 4 in the service position while the rod 13 and its handle 18 constitute means for clamping the prong to the face of the head with varying pressures, it being obvious that the extent of pressure with which the prong is drawn against the gasket 19 in the port 11 of the head is dependent upon the extent to which the rod 13 is screwed into the threaded opening 15 of the head B.

The convenience incident to having the interchange coupling 12 always with the connector is a pronounced one, experience having proven it objectionable to carry the interchange separately of the head or the connector. Various changes of a detail character may, of course, be made in my improvement without departing from the scope of my invention, and while I have illustrated a practical form thereof I do not wish to be limited to the exact construction disclosed.

What I claim is:

1. In an automatic train pipe connector, the combination with a suitable support, of a coupling head carried thereby and having a guiding prong connected to the head and adapted to be folded across the face thereof, said head and prong having cooperating ports for the purpose described. 50
2. In an automatic train pipe connector, 10 the combination with a suitable support, of a coupling head carried thereby, said head being provided at one side with a guiding prong pivoted to the head, means for permitting adjustment of the prong with respect to the head, and means for locking the prong in the adjusted position. 55
3. In an automatic train pipe connector, 15 the combination with a suitable support, of a coupling head carried thereby and provided at its side with a bearing, a guiding prong mounted on said bearing, means for permitting adjustment of the prong on the bearing whereby the prong may be shifted relative to the face of said head, means for 60 rigidly locking the prong in the normal service position, means to permit the prong to be swung from this position into the plane of the face of said head, and means for locking the prong in said plane. 65
4. In an automatic train pipe coupling, 20 the combination with a suitable support, of a coupling head carried thereby and having a guiding prong and provided also with an aperture, an interchange coupling carried 70 by said prong, and means for shifting said interchange coupling into communication with said aperture. 75
5. In an automatic train pipe connector, 25 the combination with a suitable support, of a coupling head carried thereby and having an aperture, guiding means movably mounted on said head, an interchange device carried by said guiding means, and means permitting said guiding means to be folded 80 across the face of said head to bring said interchange into alignment with said aperture, whereby the hose of a car not having the automatic connector may be connected into 85
- interchange communication with said coupling head. 90
6. In an automatic train pipe connector, 95 the combination with a suitable support, of a coupling head carried thereby and having an aperture, a guiding prong movably mounted on said head, an interchange device carried by said prong, means permitting said prong to be folded across the face of said head to bring said interchange into alignment with said aperture, whereby the hose of a car not having the automatic connector may be connected into interchange communication with said head, and means for locking the prong in the folded position. 100
7. In an automatic train pipe connector, 105 the combination with a suitable support, of a coupling head carried thereby, means pivoted on said head and operating under certain conditions to align the head with a counterpart head and under other conditions to couple said head into interchange communication with a car not equipped with the automatic connector. 110
8. In an automatic train pipe connector, 115 a coupling head having a port, a guiding prong connected to said head and movable relative thereto, said prong also having a port adapted to cooperate with the port in said head. 120
9. In an automatic train pipe connector, 125 a coupling head having a coupling face provided with a port, a guiding prong secured to said head and having a portion movable into position adjacent said face of the head, said portion of the prong having a port adapted to cooperate with the port in said head. 130
10. In an automatic train pipe connector, 135 a coupling head having a coupling face provided with a port, a prong for guiding said head into cooperative relation with a mating head, said prong being movable relative to said head and having a port adapted to cooperate with the port in said head. 140

In testimony whereof I hereby affix my signature.

JOSEPH ROBINSON.
